SIGNALING SYSTEM

Mark H. Hovey, Madison, Wis., assignor to The
Union Switch & Signal Company, Swissvale,
Pa., a Corporation of Pennsylvania

Application January 12, 1931. Serial No. 508,135

7 Claims. (Cl. 246—41)

This invention relates to railroad signaling systems of the A. P. B. (absolute, permissive, block) type, designed to control traffic in both directions on a single track, though in some aspects it is capable of more general use. It has been illustrated as including that part of the system adjacent a passing siding for controlling trains moving in one direction only, the remainder of the system for controlling the other direction 10 having been omitted for the sake of clarity.

In one aspect the invention includes means whereby a train approaching a siding from one direction, as from the west, will not only set up a danger signal to prevent a train from leaving that siding in the opposite direction, but also will set up two caution signals to warn trains approaching the siding from the other direction as from the east that a train is approaching the siding somewhere ahead. In another aspect the invention includes a directional relay and its control, which is suitable for general signaling use, though it has been illustrated as forming a part of the above described system for which it is especially suitable.

The invention accomplishes several objects, the basis of which is providing a system which performs the usual A. P. B. functions for reliably setting up on the opposite side of a siding from the train approaching the siding, two spaced caution signals and for making the one of these which is closest to the siding turn to danger when the train approaches within a certain distance of the siding. Although this object has been accomplished formerly this invention accomplishes at the same time the additional object of securing this result at greater economy by the omission of any extra relays for accomplishing the above result. In other words, it may be said that this invention accomplishes an old result with simplified apparatus and in fact without the use of a relay which was formerly considered necessary. In its other aspect, the invention provides a directional scheme including a normally energized directional relay and control circuits therefor which include both the pick-up circuit and a holding circuit, the latter operating without either a stick contact or a resistance outside of the relay. Applicant has finally accomplished all of this in an entirely satisfactory manner, the full strength of the battery being used and the system being entirely dependable.

With these and various other objects in view, the invention may consist of certain novel features of construction and operation, as will be more fully described and particularly pointed out in the specification, drawing and claims appended hereto.

In the drawing, which illustrates an embodi-

ment of the device, and wherein like reference characters are used to designate like parts,

The figure is a diagrammatic illustration of that part of the complete system which controls one direction of the two-direction traffic adjacent the passing siding, certain parts being eliminated for the sake of simplicity.

Although this invention may take many forms, only one has been chosen for illustration. The signals which are controlled by the portion 70 of the signaling system shown are numbered 1, 3 and 5, all controlling traffic in one direction, which in the present instance, is westbound, or from right to left. There would normally be additional signals 7, for controlling traffic in the 75 same direction, and additional signals not numbered for controlling traffic in the opposite direction.

According to the usual custom, the track is divided into insulated track sections A, B, C, D 80 and E, each of which has a battery connected to the rails at one end, and a track relay connected to the rails at the opposite end. The track relays are numbered 9—A, 9—B, 9—C, etc. Each of these relays operates an armature having one or 85 more circuit controllers thereon, the connections of which will be described below. There is also a passing track or siding F insulated from the other rails.

As far as possible the circuits for controlling signal 1 are numbered between 100 and 199, the circuits for controlling signal 3 between 300 and 399, and the circuits for controlling signal 5 between 500 and 599. Where the circuits are clearly duplicated on each of the three signals they will be described for one signal only, it being understood that the numbering system for the other signals is the same with the change of the hundreds digit.

The signal lamp circuits are alike for each signal, so only those for signal 1 will be described. The circuit for lighting the green lamp at signal 1 is numbered 101, the circuit for lighting the yellow lamp is numbered 103 and the circuit for lighting the red lamp is 105. Where a single wire has been used for all three circuits, it has been given three numbers, and where a single wire has been used just for circuits 101 and 103 it has been given both of those numbers. All of 110 the lamp circuits for signal 1 include the battery 11, all those of signal 3 include the battery 13, all those of signal 5 include battery 15.

The three circuits 101, 103 and 105 are controlled jointly by line relay 107, the armature 115 of which carries circuit controllers 108, 109 and 110, and by repeater line relay 111 the armature of which carries the circuit controllers 112 and 113. The controller 113 connects the battery alternatively to controller 110 for the green and 120

yellow lights, or to circuit 105 for the red light. When controller 113 is closed to connect controller 110 to the battery, then this latter controller connects alternatively the circuits 101 and 5 103, completing 101 to the green light when in the position shown (left) and completing 103 to the yellow light when in the righthand position.

As indicated by the drawing, the armature of relay 107 is a two-position polar armature its 10 position being controlled by the direction of the current flowing through relay 107. At the station of signal 3 the line relay is numbered 307 and the repeater line relay 311. At the station of signal 5, the line relay is numbered 507 and 15 repeater line relay 511. The controllers are numbered according to the same system used at the station of signal 1, relay 311 having the additional armatures 315 and 316 and the relay 511 having additional armatures 514, 515 and 516. At the 20 station of signal 5 there is located a directional relay 517 which controls an armature carrying circuit controllers 518, 519 and 520.

The line relays 107 and 111 are normally energized through the line circuit 125 (shown in 25 heavy lines), which is controlled in part at the station of signal 3 and in part at the station of signal 5. The circuit 125 may be traced from battery 15 through controllers 519 and 520, through controllers 315 and 316, through track 30 relay controllers 125—D to the line relay 107, and also to repeater line relay 111 through the branch circuit 126. The branch circuit 126 normally extends from circuit 125 at line relay 107 through armature 109 to repeater line relay 111 and back 35 through controller 108 to circuit 125 at line relay 107. When the polarity in line circuit 125 is reversed the controllers 108 and 109 flip to the righthand side and reverse the connections between branch circuit 126 and the line circuit 125 40 using insofar as necessary the reversal connections 126—R. This has the effect of preventing the reversal of current in repeater line relay 111. The reversal of the current in circuit 125 may be accomplished by the shifting of the controllers 519 45 and 520 or by shifting of the controllers 315 and 316. When the controllers 315 and 316 are shifted, the branch circuit 125—R connected to battery 13 is switched into circuit 125 in place of the portion 50 of the circuit 125 which extends to battery 17.

During the reversal above described, it is usually desirable that the repeater line relay 111 maintain its armature in its front or picked-up position. To accomplish this result the line repeater 55 relays 111, etc., are made slow releasing in any well known manner as by providing a number of copper washers on one of the cores. In order to prevent setting up a clear signal at an improper time as when a single car is merely passing from one track section to another, the line repeater relays 111, etc., are also constructed to have a retarded pick-up. This is accomplished by providing a retardation coil which is of lower conductance-turns than the main pick-up coil and opposed thereto. This retardation coil is normally 60 disconnected, but is connected whenever the relay releases the controller 112. It is preferably located adjacent to the armature, so as to have its major effect during the initial energizing period and retard the effectiveness of the main pick-up 65 coil. The construction of this relay is disclosed in my co-pending application Serial Number 480,081, filed September 6, 1930, and the combination of this relay with the novel type of line relay 107 is disclosed in my co-pending application Serial Number 499,886, filed December 4, 70

1930 and claimed in my copending application Serial No. 520,422, filed March 5, 1931.

The line relays 307 and 311 are normally energized by a line circuit 325 with its branch 80 326 to the repeater line relay 311. The circuit 325 may normally be traced from the battery 15 through controller 516 to relay 307 and back through controller 325—C to junction point 25 and from there through controller 325—B to junction point 27 and back to the battery 15 through controller 85 515. Junctions 25 and 27 are also normally connected by directional branch circuit 325—D through controller 518 operated by the directional relay.

Line relays 507 and 511 are normally energized 90 through circuit 525 shown in heavy lines. This circuit may be traced from battery 17 at the station of signal 7 through controllers 715 and 716 through controller 525—B controlled by track section B to the line relays 507 and 511. The controllers 715 and 716 are controlled by line relay 711. It should be understood that this relay 711 is controlled directly by track circuit A through track relay 9—A and indirectly by the track circuits ahead (to the west), not shown, 100 through what is known as the tumble-down system, one form of which is disclosed in my application Serial No. 499,886. The control circuit for relay 711 is similar to that of line circuit 525.

105 Directional relay

The directional relay 517 is preferably wound with two separate coils, one of which is of sufficiently lower conductance-turns than the other so that under the influence of a given voltage said 110 coil of lower conductance-turns will only hold the armature if it has been previously picked up by the other coil. The pick-up coil may properly comprise 21,000 turns of #31 copper enameled wire having a resistance of 11,000 ohms, in which 115 case the holding coil could be made up of 7500 turns of the size #28 wire made of what is known as number 30 alloy and having a resistance of 525 ohms. The term conductance-turns is used as the convenient manner of indicating a characteristic 120 of the relay corresponding to the more common term ampere turns, which latter, however, is dependent on the voltage to which a coil is submitted.

The pick-up coil of directional relay 517 is 125 normally energized by circuit 530 which may be traced from the relay coil 517 through the upper contact of armature 514 to the battery 15 and back to relay 517. The holding circuit 531 or the circuit for holding coil of relay 517 may be 130 traced through relay 517 through armature 531—B to the battery 15 and back to the relay 517. There is a second holding circuit 532 which is in part common with holding circuit 531 but branches off therefrom at junction 26 and goes 135 to the battery through a controller 514 and its back contact.

140 Tumble-down operation

Although the tumble-down operation has been 140 fully described in the second of my copending applications mentioned above, it may be briefly summarized here. If a train is moving eastward (toward the siding F) on track section A or on any of the sections to the west thereof by which line relay 711 is indirectly controlled, this relay is de-energized. This releases the armature and shifts controllers 715 and 716 to break the circuit 525. The breaking of the circuit 525 de-energizes line 145 relays 507 and 511. De-energization of 511 per- 150

mits the release of its armature, after the elapse of the releasing period, and this shifting of the controllers of relay 511 would have the primary effect of breaking the green lamp circuit 501 by 5 lowering controller 513 and of completing the danger lamp circuit 505 through the lower contact of controller 513. This de-energization would also have the secondary effect of shifting the controllers 315 and 316 to their back position 10 reversing the polarity of current in circuit 325. This reversal of current in circuit 325 causes the controller 310 to flip to the righthand position, and thereby break the green lamp circuit 301 and complete the caution lamp circuit 303.

15   *Operation of the directional relay*

If a train now be imagined as traveling westward and about to enter track section B the parts relating to signal 5 and to the directional relay 20 would be as shown in the drawing. As the train entered section B it would shunt track relay 9-B simultaneously releasing controllers 525-B and 531-B. The release of 531-B would immediately close the holding circuit 531 for directional relay 517 and since that relay was at that time energized, the holding circuit would be sufficient to maintain the controllers in their front position as shown. The releasing of controller 25 525-B would cause the de-energization of relay 511, but due to the slow release of the relay 511 its controllers would not shift until after the holding circuit 531 had been closed, as described. The controller 514 with the others would then 30 shift, breaking the pick-up circuit 530, but this 35 would have no effect due to the fact that the holding circuit was previously closed. In its new position (against its back contact) controller 314 would complete the second holding circuit 532. This second holding circuit would be effective to 40 maintain the directional relay 517 energized as long as the repeater line relay 511 remained de-energized. In other words, the second holding circuit prevents the release of the directional 45 relay when the first holding circuit is broken by the pick-up of armature 531-B. It should be understood that although omitted for the sake of simplicity, there would usually be a second track section between the signal 5 and the signal 7 so that while the train was on that track section the second holding circuit would be necessary to keep the directional relay 517 energized. The directional relay 517 serves two functions. The first of these, which is of general utility, is 50 to prevent the operation of the tumble-down feature when the train is travelling in the directions governed by the signals. Thus in the present instance, if a train were travelling westward, as described, it would release the controller 325-B and make a break at that point in the line circuit 325 which controls the signal 3 through line relay 307 and 311. The directional relay 517 by 55 maintaining the armature 518 in its front position nullifies the effect of the break at 325-B and maintains the circuit 325 closed through its directional branch 325-D which includes the controller 518.

When the train is travelling eastward, the line repeater relay 511 is de-energized through the tumble-down feature described above and the pick-up circuit through the controller 514 is therefore broken before the train reaches section E. Since the holding circuit 531 is not completed when the pick-up circuit is broken, the directional relay 517 becomes de-energized. The completion of the holding circuits, either by the

release of controller 531-B or the complete release of controller 514, would then be ineffective to cause the pick-up of relay 517 since the excitation of the holding coil is too weak to accomplish this result. The relay 511 and also 80 the other relays, is of the commercial form with a spring at the front contact having the effect of breaking the circuit through the front contact before the relay has become sufficiently de-energized to release the armature all the way to the back contacts. Thus there is a sufficient time interval between the opening of pick-up circuit 530 and the closing of holding circuit 532 for the directional relay to become de-energized. When the train reaches track section B it releases armature 325-B thus breaking at that point the circuit 325. As the directional branch 325-D of this circuit 325 is already broken by armature 518 this break at 325-B would be effective and the line relays 307 and 311 would be de-energized thus setting up a danger indication at the signal 3 by completing circuit 305.

85   *The double caution signal*

When a train is travelling east toward siding F it is desirable to set up signals at 1 and 3 to advise a westbound train to expect to stop or pass at the siding. In other words, it is desirable that as soon as a train leaves the siding (not shown) next toward the left of the siding 105 shown, first that the tumble-down system set up a danger indication at the signals 5 and 7 and second that the signals 3 and 1 be made to indicate caution so that a train passing signals 1 and 3 in the direction controlled thereby will be 110 advised that it must wait at the siding and possibly find the other train already there. Signal 3 is set to caution when controller 310 flips to the right in response to a reversal of current in line circuit 325. The line current is reversed by 115 the shifting of controllers 515 and 516 when line repeater relay 511 is de-energized in the operation of the tumble-down feature already described.

The second function of the directional relay 517 120 is to set up an extra caution signal on the right of the siding (at signal 1) whenever a train is on the left of the siding and travelling toward the siding, and to set up a clear indication at signal 1 when a train in the same position is travelling 125 away from the siding. As previously described, when a train is in track section A or any of the track sections to the left thereof, the tumble-down system operates to cause the release of line relays 507 and 511 and also of directional 130 relay 517. The release of directional relay 517 shifts the armatures 519 and 520 reversing the connections of battery 15 to circuit 125. This reverses the polarity of current in circuit 125 and causes the polar armature of relay 107 to 135 flip to the right. When the controller 110 flips to the right it breaks the green lamp circuit 101 and completes the caution lamp circuit 103. As the train travels on through section A and into section B the repeater line relay 311 is de-energized as above described. This causes the shifting of controllers 315 and 316 to disconnect battery 15 from the circuit 125 and connect battery 13 in its place, but battery 13 is also connected in reverse polarity so that there is no effect on signal 1, the yellow lamp circuit 103 remaining completed. When the train clears track section B, the directional relay 517 picks up, shifts the controllers 519 and 520 to their normal position. When the train also clears track section C, 140

- the repeater line relay 311 will be energized and the controllers 315 and 316 will be shifted to their normal position to reconnect battery 15 to incomplete line circuit 125. The result of this 5 is that as soon as the train clears track section D so that relay 9—D is energized, the circuit 125 is completed with normal polarity so that the controller 110 flips back to the left, as shown, completing the circuit 101 for the green lamp.
- 10 If we suppose that a westbound train is located in section C the track relay 9—C will be de-energized and the line relay 307 and 311 will likewise be de-energized. The de-energization of line relay 311 will cause the shifting of armature 313 to complete the circuit 305 for the red lamp and break the circuits 301, 303 for the proceed indications. The release of armatures 315 and 316 will set up a caution indication at signal 1 by connecting battery 13 in circuit 125 in reversed polarity as described. As the westbound train moves into track section B it sets up the holding circuit 531 for the directional relay 517 by releasing the controller 531—B to its back contact. This maintains the controllers 519 and 25 520 in their front position so that the battery 15 is connected with normal polarity. Therefore, when the train clears track section C the track relay 9—C picks up to complete the circuits 325 and 326 to relay 311, drawing controllers 315 and 30 316 to their front contacts to connect the battery 15 to the circuit 125. As the battery is connected in normal polarity the caution indication of signal 1 changes to clear indication, although, as has been seen, if the train were in the same section 35 but moving toward siding F, signal 1 would indicate caution, due to de-energization of directional relay 517.
- The usual permissive indication is maintained at signal 3 so long as the train is in block or section B. This indication is secured by means of controllers 515 and 516 which through their back contacts connect battery 15 in reverse polarity to line circuit 325 so that the line relay 307 is energized with reverse polarity and its controller 310 45 flips to the right, completing yellow lamp circuit 303. It should be noted that the repeater line relay 511 had become de-energized by the shunting of track relay 9—B with the consequent release of the armature 525—B to break line circuit 525 through which together with branch line circuit 526 repeater line relay 511 is energized.
- 50 It is to be understood that I do not wish to be limited by the exact embodiments of the device shown, which are merely by way of illustration and not limitation, as various and other forms of the device will of course be apparent to those skilled in the art without departure from the spirit of the invention or the scope of the claims. It should be understood that in the claims such old terms as signals, trackway, relay, etc. are used in an extremely broad sense, including all equivalents, such, for example, as automatic train control apparatus.
- I claim:
- 65 1. A railway signaling system including a trackway having forward, intermediate and rear blocks, forward, intermediate and rear signals controlling the entrance of each block; a directional relay having a pick-up coil and a holding coil of lower conductance-turns than the pick-up coil, means for rendering said holding coil ineffective when said trackway is occupied by a train travelling in the direction not controlled
- by said signals only; a circuit in part controlled by said directional relay for controlling said intermediate signal, and a circuit controlled as to polarity by said directional relay for controlling said rear signal. 80
2. A railway signaling system including a trackway having forward, intermediate and rear blocks, forward, intermediate and rear signals controlling the entrance of each block; a directional relay having a pick-up coil and a holding coil of lower conductance-turns than the pick-up coil, means for rendering said holding coil ineffective when said trackway is occupied by a train travelling in the direction not controlled by said signals only; a circuit in part controlled by said directional relay for controlling said intermediate signal, and a circuit directly controlled in part by said directional relay for controlling said rear signal. 85
3. A signaling system including a trackway divided into forward, intermediate and rear track sections; rear traffic control means, including a line relay, for governing the entrance of trains into the rear section, intermediate traffic control means governing the entrance of trains onto the intermediate section, and directional means controlled by the direction of traffic in the forward sections of track for controlling both said intermediate means and said rear line relay directly. 90
4. A railroad signaling system including a trackway, a directional relay controlled by the direction of traffic on said trackway, a pair of signal relays having line circuits, and controllers on the armature of said directional relay for controlling the continuity of the circuit for one signal relay 105 and the polarity of the circuit for the other signal relay. 110
5. A railroad signaling system including a trackway, a signal relay, a line circuit for said signal relay and a switch for connecting said line circuit to two batteries alternatively, and a polarity switch for reversing the polarity of connection of one of said batteries. 115
6. A railroad signaling system including a trackway, a signal relay, a line circuit for said signal relay and a switch for connecting said line circuit to two batteries alternatively, and a polarity switch for reversing the polarity of connection of one of said batteries, said polarity switch being operated in response to the direction of 120 traffic on said trackway. 125
7. A signaling system comprising a plurality of track sections and a signal controlling traffic through said track sections in one direction, a track relay operated by each of said track sections, a line relay controlled by two of said track relays, a directional relay including relay coils and pick-up and holding circuits which energize said coils, said holding circuit including coils having a resistance enough higher than the coils included in said pickup circuit so that with a given voltage the pickup circuit will be capable of causing said relay to pick up, but the holding circuit will be incapable of causing said relay to pick up but will be capable of maintaining it in position after it has been picked up, said pickup circuit being controlled by said line relay and said holding circuit being controlled in part directly by one of said track relays, a polar relay for controlling said signal, and pole-changing means operated by said 130 directional relay for controlling said polar relay. 135
